UNITED STATES PATENT OFFICE.

CURTIS HUSSEY VEEDER, OF HARTFORD, CONNECTICUT, ASSIGNOR TO THE VEEDER MANUFACTURING COMPANY, OF HARTFORD, CONNECTICUT, A CORPORATION OF CONNECTICUT.

INDICATOR FOR MAGAZINE-GUNS.

1,332,936.

Specification of Letters Patent.

Patented Mar. 9, 1920.

Application filed January 21, 1919. Serial No. 272,242.

To all whom it may concern:

Be it known that I, CURTIS HUSSEY VEEDER, a citizen of the United States, residing in the city of Hartford, in the State of Connecticut, have invented certain new and useful Improvements in Indicators for Magazine-Guns, of which the following is a specification, reference being had to the accompanying drawing, forming a part hereof.

10 In the operation of machine guns, under conditions of actual warfare, it is desirable that the operator have knowledge of the approximate number of cartridges remaining in the magazine. In machine guns in which 15 the cartridges are fed by belts there is no need for special devices to indicate the approximate number of cartridges available because the belt itself is under the observation of the operator, but in machine guns of 20 the Lewis type, in which the cartridges are concealed from sight within the magazine there is need for a special device to indicate to the operator at least the approximate number of cartridges which remain in the 25 magazine so that, when the supply of cartridges is about to become exhausted, a full magazine may be in readiness to be substituted quickly for the empty magazine. The present invention has for its general purpose 30 to meet this need and in accordance with the invention there is fixed upon one portion of the magazine a counting mechanism and means are provided whereby such counting device is actuated through the relative 35 movement of one part of the magazine with respect to another. In the Lewis gun the magazine usually carries ninety-seven cartridges and the counting mechanism is therefore preferably arranged to indicate 40 from ninety-seven down to zero, so that a glance at the counting mechanism will show to the operator the number of cartridges which remain in the magazine at any time. The invention will be more fully explained 45 hereinafter with reference to the accompanying drawing in which it is illustrated and in which—

Figure 1 is a top view of a magazine for a Lewis' machine gun with the indicating mechanism applied thereto.

Fig. 2 is a view of the same in side elevation with portions of the casing and of the internal devices broken away.

Fig. 3 is a detail view in section on the 55 plane indicated by the broken line 3—3 of

Fig. 1, looking in the direction of the arrows, on a larger scale than that of Fig. 1.

The magazine to which the invention is shown to be applied in the present instance is the ordinary magazine of the well known 60 Lewis machine gun, comprising a cylindrical casing *a*, with the obliquely disposed separating and guiding bars *b* and vertical separating and guiding pins *c*, a hub *d* formed to fit upon the support provided therefor 65 on the gun and to receive the casing *a* and provided with a stepped, spiral flange *e*, a carrying bar *f*, provided with a carrying strap *f'*, and a locking bar *g* arranged to slide within the carrying bar *f*. All of these 70 parts are arranged and operate in the usual manner. The casing *a* is rotated upon the hub *d* by any usual or suitable devices, not necessary to be shown or described.

In the embodiment of the invention illustrated the top plate *a'* of the casing is provided, about its central opening, with an internal gear *a''* and preferably has secured thereto also a ring *a'''* which overlaps and covers the internal gear *a''*.

On the top plate *d'* of the hub *d* is mounted the counting mechanism which may be of any suitable construction. As shown in the drawing the casing *h* of the counting mechanism, having a window *h'* and a central 85 hub *h''*, is secured to the plate *d'* by a bolt and nut *h''*. Mounted loosely on the hub *h''* is a gear *i* which meshes with the internal gear *a''* above described. Also mounted on the hub *h''* are the two index rings *k* and *k'*, 90 units and tens, with the transmission gear *k''*, all constructed and arranged to operate as usual. By means of a pin *i'* or other suitable connection, the gear *i* is operatively connected to the units wheel *k*. The number 95 wheels or rings *k* and *k'* have the digit figures arranged thereon in such order that when the magazine is full the counting mechanism shall indicate ninety-seven and, in the successive operation of the mechanism, shall number down to zero.

In the operation of the invention as illustrated in the drawing, the magazine casing *a* receives, in the operation of the gun, a step-by-step movement, which, through the 105 gears *a''* and *i*, actuates the counting mechanism, causing it to show at the window *h'* the number of cartridges which remain in the magazine.

It will be obvious that various changes in 110

details of construction and arrangement can be made to suit different conditions of use and that, except as pointed out in the accompanying claims, the invention is not restricted to the precise construction shown and described.

I claim as my invention:

1. The combination with a magazine for machine guns comprising a central supporting hub and a cartridge carrying casing mounted rotatably on the hub, of a counting mechanism mounted on the hub, a driving gear carried by the casing and a driven gear carried by the hub in mesh with the driving gear and in operative connection with the counting mechanism.

2. The combination with a magazine for machine guns comprising a central supporting hub and a cartridge carrying casing mounted rotatably on the hub, of an internal driving gear fixed to said casing and a counting mechanism fixed to said hub, said counting mechanism comprising a casing with a window and a central hub, number rings mounted on the hub and a gear mounted on the hub in mesh with said internal gear and in operative engagement with one of the number rings.

This specification signed this 18th day of January, A. D. 1919.

CURTIS HUSSEY VEEDER.
